UNITED STATES PATENT OFFICE.

NICOLAS SACCOCIA, OF CRANSTON, RHODE ISLAND, ASSIGNOR TO FULFORD MFG. CO.,
OF PROVIDENCE, RHODE ISLAND, A CORPORATION OF RHODE ISLAND.

DESIGN FOR A METAL NECKLACE OR SIMILAR ARTICLE.

Application filed November 18, 1927. Serial No. 24,202. Term of patent 3½ years.

To all whom it may concern:

Be it known that I, NICOLAS SACCOCIA, a citizen of the United States, residing in the city of Cranston, county of Providence, and State of Rhode Island, have invented a new, original, and ornamental Design for a Metal Necklace or Similar Article, of which the following is a specification, reference being had to the accompanying drawing, forming a part thereof.

Figure 1 is a front view and Figure 2 is an enlarged view partly in section of a metal necklace or similar article, showing my new design.

I claim:

The ornamental design for a metal necklace or similar article, substantially as shown.

NICOLAS SACCOCIA.
